UNITED STATES PATENT OFFICE.

HERMANN ARON, OF CHARLOTTENBURG, GERMANY.

APPARATUS FOR ELECTRICALLY WINDING UP DRIVING-SPRINGS.

SPECIFICATION forming part of Letters Patent No. 700,597, dated May 20, 1902.

Application filed February 20, 1902. Serial No. 94,899. (No model.)

To all whom it may concern:

Be it known that I, HERMANN ARON, a subject of the King of Prussia, German Emperor, residing at No. 39 Wilmersdorferstrasse, 5 Charlottenburg, in the Kingdom of Prussia, German Empire, have invented certain new and useful Improvements in Apparatus for Electrically Winding up Driving-Springs, (for which I have made application for Letters 10 Patent in Germany, dated July 2, 1901, Serial No. A 8,196,) of which the following is a specification.

My invention relates to apparatus for electrically winding up driving-springs for clock-work, electric meters, and similar instruments, and particularly to that class of devices in which the driving-spring serves as a part of the electric circuit.

In the accompanying drawings, Figure 1 is 20 a front elevation of a device for electrically winding up a driving-spring, the working parts being shown in one extreme position; and Fig. 2 is a corresponding front elevation 25 showing the working parts in their opposite extreme position. Fig. 3 is a side elevation of the device shown in Figs. 1 and 2. Fig. 4 is a front elevation of part of a device embodying a modification of the construction of 30 Figs. 1, 2, and 3 and showing the essential parts in one extreme position. Fig. 5 is a corresponding front elevation showing the essential parts in the opposite extreme position. Fig. 6 is a side elevation of the construction of Figs. 4 and 5.

Referring to the drawings, *a* denotes a horseshoe-magnet provided with a coil *q*, and *b* is a swinging armature pivotally mounted on the shaft *c*, to which is fixed a ratchet-wheel *c'*, said armature being movable between the poles of the magnet. The armature *b* is provided with a spring-pressed driving-pawl *b'* and with an arm *b*², and to said arm is connected one end of the driving-spring *s*; the other end of said spring being 45 connected to the frame, which is stationary with the magnet. A tilting device or lever is pivoted at *i* to the frame and comprises the arms *k* and *l*, between which is a pin or stud *h* on the arm *b*², movable with the armature 50 *b*. The arm *k* of the tilting device or lever

is of conducting material, as is also the pin *h* and arm *b*², and to which arm the driving-spring *s* is electrically connected, said spring also forming part of the circuit for the electric current. The arm *k* may be provided 55 with a conducting contact-plate *h'* to bear against the pin or stud *h*. The tilting device or lever comprising the arms *k* *l* is controlled by a spring *m*, one end of which is attached to a stationary pin *m'* on the frame of 60 the structure and the other or free end of which is attached to a pin *m*² on the tilting device or lever above the pivot *i* of the latter, so that said spring serves to cause the said tilting device or lever to move quickly 65 to one side or the other of its pivotal point *i* after said spring has in the movement of said tilting device in either direction passed the dead-center or position of equilibrium represented by the pivotal point *i*. The arm *l* 70 of the tilting device is of insulating material, so that when the pin *h* is in contact with said arm *l* the circuit will be open and the current interrupted; but when the said pin *h* is in contact with the arm *k* the circuit will be 75 closed. The swinging armature is provided with a pin *t*, which is arranged to engage an insulating-block *v* on the arm *k* for the purpose of insuring a proper movement of the tilting device or lever in case the spring *m* 80 should fail to properly control its tilting movement in such a manner as to cause the conducting-arm *k* to come in contact with the pin *h*.

The operation of the construction thus far 85 described is as follows: When the conducting-arm *k* of the tilting device or lever is forced into contact with the pin *h*, the circuit is closed and the magnet is energized in such a manner as to suddenly swing the armature *b* from the position shown in Fig. 1 to the position shown in Fig. 2, thereby winding up the driving-spring *s* or putting the same under tension. In this sudden swinging movement of the armature to the left, Fig. 1, 90 the pin *h*, movable therewith, will cause the tilting device to move toward the position shown in Fig. 2 until the point of attachment of the spring *m* with the tilting device passes by the pivotal point *i* of the said tilting de- 95 100

vice, when the said spring will cause the said tilting device to suddenly change its position, so as to free the conducting-arm *k* from contact with the pin *h*, thereby breaking or opening the circuit. The force of the driving-spring *s* will now be utilized to drive the clock-work connected with the shaft *c* by reason of the fact that the tension of said spring will be exerted through the arm *b*², fixed with relation to the armature *b*, causing the pawl *b'* on the armature to drive the ratchet-wheel *c'* and the clockwork operated from the shaft *c*, with which said ratchet-wheel is connected, so long as the tension of the spring *s* is sufficient to effect this result. As the armature *b* slowly swings from the position shown in Fig. 2 to the position shown in Fig. 1 under the stress of the driving-spring *s* the pin *h*, moving with said armature and in contact with the insulated arm *l* of the tilting device, causes said tilting device to move toward the position shown in Fig. 1 until the free end of the spring *m* can pass the pivotal point *i* of said tilting device, when the said spring will cause the tilting device to swing suddenly into such position as to cause its conducting-arm *k* to come in contact with the pin *h*, thereby closing the circuit and causing the armature to swing quickly back to the position shown in Fig. 2 and again wind up or put under tension the driving-spring *s*.

In the operation just described when the armature is moving from the position shown in Fig. 2 toward the position shown in Fig. 3, if, for any reason, the spring *m* should fail to cause said tilting device to move to a position to close the circuit, or if any sparking, which is likely to occur, tends to force the conducting-arm *k* out of contact with the pin *h*, and thereby open or tend to open the circuit, such a faulty or improper operation will be guarded against and prevented by the pin *t* moving with the armature *b* and arranged to strike the insulating-block *v* on said arm *h*, so as to force the said conducting-arm *k* into contact with the pin *h* and hold it in such contact until the winding operation of the spring has been effected, the said arm *k* being at such time held strongly and steadily between the pins *t* and *h*.

In the modified construction shown in Figs. 4, 5, and 6 and the operation of which is the same as that of the construction shown in Figs. 1, 2, and 3 the arm *l* of the tilting device is omitted and the pin *t* is provided with an insulating-roller *u* for contact with the arm *h* to force the tilting device over the dead-center should the spring *m* fail to perform its office to this end and also serving the purpose of the non-conducting arm *l* in that the said roller *u* serves to start the tilting device toward its position of equilibrium when the driving-spring *s* is effecting the return movement of the armature as the spring is being

unwound in driving the clockwork or performing other equivalent duty. In fact, this modified construction is preferred for some purposes, in that it is better for use in connection with high-tension currents, as in the construction of Figs. 1, 2, and 3 the arm *l* of the forked tilting device sometimes causes said tilting device to move too quickly or sooner than it need to and causes too much sparking, while the insulating-roller *u* of the modified construction rolls smoothly along the arm *h*, thereby gradually forcing the same into a position of equilibrium and throwing it into its opposite position as the spring *m* passes the pivotal point or center of motion of the tilting device or lever. In either form of the invention the tilting-device controller, moving with the armature as the latter is returned by the driving-spring and represented in one instance by the pin or stud *t* and in the other by the roller *u*, is deemed important in that when the circuit is broken and the coil *q* cut out such a movement of the tilting device will always be insured by said controller as will cause the current to be closed and the stress of the driving-spring restored before said spring has fully lost its driving tension, and thus the clock or other device driven by said spring cannot by failure of a proper movement of the tilting device accidentally come to a full stop. Furthermore, the controlling device not only insures the closing of the circuit at the proper times, but prevents the tilting device from being thrown back by sparking in such a manner as to break the contact between the arm *h* and the contact pin or stud *h* when the contact has once been effected until the tension of the driving-spring is restored by a movement of the armature when the latter is attracted by the electromagnet.

I claim as my invention—

1. In an apparatus for electrically winding up driving-springs, the combination with an electromagnet, of an armature arranged to swing between the magnet-poles, a contact pin or stud movable with said armature, a tilting device or lever making and breaking electrical contact with the said stud, a driving-spring arranged to be placed under tension by the movement of said armature when the latter is attracted by the said magnet; and a controlling device or stud, moving with said armature, for assisting the tilting motion of the said tilting device or lever, and for keeping the same from being thrown back by sparking, substantially as and for the purpose set forth.

2. In an apparatus for electrically winding up driving-springs, the combination, with an electromagnet, of an armature arranged to swing between the magnet-poles, a contact pin or stud movable with said armature, a tilting device or lever making and breaking

electrical contact with the said stud, a driving-spring arranged to be placed under tension by the movement of said armature when the latter is attracted by said magnet, a con-
5 trolling-stud movable with said armature, and an insulating-roller carried by said stud to strike the tilting lever for assisting its tilting motion and for keeping the same from

being thrown back by sparking, substantially as and for the purpose set forth. 10

In witness whereof I have hereunto set my hand in presence of two witnesses.

HERMANN ARON.
